Halley C. Dolan,

UNITED STATES PATENT OFFICE.

HALLEY C. DOLAN, OF DETROIT, MICHIGAN, ASSIGNOR OF ONE-HALF TO MALCOLM J. MCLEOD, OF DETROIT, MICHIGAN.

SIGNAL.

1,268,695.

Specification of Letters Patent. Patented June 4, 1918.

Application filed March 31, 1917. Serial No. 158,783.

To all whom it may concern:

Be it known that I, HALLEY C. DOLAN, a citizen of the United States of America, residing at Detroit, in the county of Wayne and State of Michigan, have invented certain new and useful Improvements in Signals, of which the following is a specification, reference being had therein to the accompanying drawings.

10 This invention relates to signals for automobiles and has special reference to a sign exhibitor having a rotary sign adapted to be intermittently actuated by electrical devices to display a desired sign.

15 My invention aims to provide a novel electrically operated mechanism for actuating a rotary sign member, so that the member may be easily, quickly and accurately positioned to display a sign thereon.

20 The mechanism is necessarily compact and of such construction as to withstand jars and vibrations to which it is subjected when carried by an automobile or similar vehicle, and in constructing the exhibitor, I have 25 aimed to reduce the number of parts to a minimum and cut down as much as possible on weight, so that the exhibitor can be easily and safely carried on a bracket or other part of an automobile.

30 The construction of the signal will be hereinafter described and then claimed, and reference will now be had to the drawings, wherein—

Figure 1 is a front elevation of the signal exhibitor, partly broken away, and partly in section;

Fig. 2 is a vertical cross sectional view of the same;

Fig. 3 is a front elevation of a rotary sign member;

Fig. 4 is a diagrammatic view illustrating the electrical devices and the connections thereof.

The signal exhibitors, as now constructed, include a cylindrical casing 1 having a rear wall 2 and a detachable front wall 3. The front wall 3 is provided with a central opening 4 for a lens or bull's-eye 5 and above the opening 4 is a segment shaped opening 6 closed by a transparent plate 7.

The rear wall 2 is provided with a socket member 8 of a conventional form adapted to receive the bracket of an automobile or similar vehicle, and connected to the rear wall 2 by bolts or tie rods 9, 10, 11 and 12 are

parallel plates 13 and 14, constituting a framework or housing for the electrically operated mechanism of the signal.

Journaled in the plates 13 and 14, centrally of the casing 1, is a pinion shaft 15 having a pinion 16. On the forward end of the pinion shaft 15 is fixed a spider 17 and suitably attached to said spider is a sign member 18. The sign member 18 is in the form of a disk having a central opening 19 and on the outer side of said member are placed suitable signs, for instance the words "Safety first" and "Stop" together with arrows which may be formed by cutting arrow shaped openings in the sign member. The sign member 18 may be of translucent material with the arrows and the characters of the words transparent or the sign member may be of opaque material with the characters of the words cut out, so that rays of light may project therethrough. In either instance, there is an incandescent lamp 20 in alinement with the casing opening 6 and said lamp is preferably carried by the rear wall 2 of the casing.

Meshing with the pinion 15 of the shaft 16 is a sector gear 21 pivoted upon a shaft 22 connecting the plates 13 and 14. The sector gear 21 has a crank portion loosely connected by a pin 23 to a bell crank 24 pivoted on a rod or shaft 25 connecting the plates 13 and 14 and the movement of said bell crank in one direction is limited by the bolt or tie rod 9. Pivots connected to the bell crank 24 is a reciprocable rod 26

slidable in a guide 27 connecting the plates 13 and 14. Another reciprocable rod 28 is slidable in the guide 27 and this rod is pivotally connected, as at 29 to an arm 30 pivoted on a rod or shaft 31 connecting the plates 13 and 14. The upper end of the arm 30 is slotted, as at 32, to provide clearance for the reciprocable rod 26 and the bell crank 24 and the upper edge of said bell crank has stepped portions 33, 34 and 35.

100 These stepped portions of the bell crank are adapted to be engaged by the arm 30 actuated by the reciprocable rod 28 to control the movement of the bell crank 24, the sector gear 21, the shaft 15, and the rotary sign member 18 by a reciprocable movement of the rod 26. Both of the rods 26 and 28 are provided with collars 36 and encircling said rods between the collars 36 and the guides 27 are coiled compression springs 37,

105

110

these springs holding the reciprocable rod in normal position, that is, with the sign member 18 displaying the sign "Safety first" at the opening 6 of the exhibitor casing.

- 5 Between the plates 13 and 14 is an electro-magnet 38 and pivoted on the bolt or connecting rod 10 is an armature 39 for said electro-magnet. The plate 13 has a stop 40 for the armature 39, the stop maintaining 10 the armature in proximity to the pole piece of the electro-magnet, and the upper end of the armature is slotted to provide clearance for the rods 26 and 28 and is adapted to engage a collar 41 fixed on the rod 26.
- 15 Another bolt or tie rod 42 connects the plates 13 and 14 and supports the pivoted armature 43 for an electro-magnet 44. The armature 43 is slotted to provide clearance for the rods 26 and 28 and said armature is 20 adapted to engage collars 45 on the reciprocable rods.

Another electro-magnet 46 is mounted between the plates 13 and 14 and this electro-magnet has an armature 47 pivoted on the bolt or rod 11. The armature 47 is slotted to provide clearance for the rods 26 and 28 and said armature is adapted to engage the collars 36 of said rods.

The plate 13 has stops 48 and 49 for the 30 armatures 43 and 47 respectively.

The cylindrical wall of the exhibitor casing has an opening 50 covered by a transparent plate 51 and this opening permits of rays of light being cast upon a license 35 card or sign in proximity to the exhibitor casing.

The rear wall of the exhibitor casing has an insulator 52 for leading wires 53, 54 and 55 to the electro-magnets 38, 44 and 46 respectively, and by reference to Fig. 4, it will be noted that the electro-magnets are grounded on the exhibitor casing or parts thereof, also the incandescent lamp 20, said lamp being connected by a wire 56 to a 40 switch 57 and said switch by a wire 58 to a suitable source of electrical energy, as batteries 59. The batteries 59 are connected to the exhibitor casing or metallic parts thereof also to a three-point switch 60 controlling the energizing of the electro-magnets of the signal.

The circuit established in connection with the electro-magnet 38 attracts the armature 39 and causes said armature to engage the 55 collar 41 and shift the rod 26 against the action of the spring 37 associated with said rod. The bell crank 33 is moved to shift the sector gear 21 and partially rotate the pinion shaft 15 and this shaft brings the 60 sign member 18 into position to display the word "Stop". The movement of the sign member 18, pinion shaft 15, sector gear 21, and bell crank 24 are limited by the arm 30 engaging the stepped portion 33 of the bell 65 crank 24.

When the electro-magnet 44 is energized, the armature 43 thereof engages the collars 45 of the rods 26 and 28, the rod 26 causing the sign member 18 to be shifted into position to display the arrow indicating 70 the direction of travel to the left, and the rod 28 causes the arm 30 to engage the stepped portion 34 of the bell crank and correctly define the position of the sign member 18.

The operation of the electro-magnet 46, armature 47 and rods 26 and 28 is somewhat similar to that of the electro-magnet 44 and the operation just described with the exception that the sign member 18 is rotated sufficiently to correctly position an arrow at the display opening 6 to indicate direction of travel to the right.

In all the operations, which are controlled by the switch 60, the springs 37 are adapted 85 to restore the mechanism to normal position after each operation.

The switch 57 permits of the incandescent lamp 20 being used at night and the spider supporting the sign member 18 will 90 allow rays of light to be cast through the bull's-eye or said bull's-eye sufficiently illuminated to indicate danger and serve as a tail light for an automobile.

It is thought that the operation and utility of the signal has been sufficiently described as to be understood, and while in the drawings there is illustrated a preferred embodiment of my invention, it is to be furthermore understood that the structural 100 elements are susceptible to such variations and modifications as fall within the scope of the appended claims.

What I claim is:—

1. In a signal, a casing having a display opening, a rotary sign member in said casing adapted to display a sign at said display opening, gearing adapted to move said sign member, a reciprocable rod adapted to actuate said gearing, electrical devices 105 adapted for moving said rod predetermined distances to position said sign member to display a sign, and means actuated by said devices adapted to define the position of said rotary sign member.

2. In a signal, a casing having a display opening, a rotary sign member in said casing adapted to be moved to display a sign at the opening of said casing, gearing adapted to move said sign member, independent 120 electrical devices in said casing and adapted to be energized to operate said gearing, and means actuated by said electrical devices adapted to control and regulate the movement of said sign member by said gearing.

3. In a signal, a casing having a display opening, a rotary sign member in said casing adapted to be moved to display a sign at the opening of said casing, gearing adapted to move said sign member, an electric- 125

cally actuated reciprocable rod for operating said gearing, and an electrically operated reciprocable rod for controlling and regulating the movement of said sign member by said gearing.

4. In a signal, a casing having a display opening, a rotary sign member in said casing adapted to display a sign at said display opening, gearing adapted to move said sign member, a bell crank adapted to actuate said gearing, an electrically actuated reciprocable rod adapted for moving said bell crank, and means on said rod adapted to restore said sign member to normal position, and means actuated in synchronism with said rod for controlling the movement of said sign member.
- 15 5. In a signal, a casing having a display opening, a rotary sign member in said cas-

ing adapted to display a sign at said display opening, gearing adapted to move said sign member, a bell crank adapted to operate said gearing, a rod connected to said bell crank, electro-magnets in said casing, armatures actuated by the energizing of said 20 electro-magnets adapted for moving said rod predetermined distances, and means actuated by said armatures and including a pivoted arm in connection with said bell crank adapted to regulate the movement of 25 30 said sign member.

In testimony whereof I affix my signature in the presence of two witnesses.

HALLEY C. DOLAN.
